AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

BOBBIN SUPPORT FOR WEFT-REPLENISHING MECHANISM.

Application filed August 14, 1925. Serial No. 50,329.

This invention relates to improvements in bobbin supports for weft replenishing mechanisms of the multi-color type and an object of the invention is to provide a support with a giveaway the end of which may yield in any angular direction with respect to the supporting structure.

In replenishing mechanisms of the type referred to bobbins are released from one of several vertical compartments and guided along supports to transfer position just prior to the descent of the transerrer arm. It sometimes happens that the bobbin moves toward transfer position irregularly and is struck by the arm before being properly placed. When this occurs it is desirable that the support yield to prevent breakage and it is accordingly a further object of my invention to provide a support so constructed that it will yield downwardly under the pressure of an improperly placed bobbin. It also occasionally happens that a bobbin will be improperly transferred into a shuttle and as it is carried rearwardly by the lay will project to engage the giveaway, and to prevent breakage under such conditions the support is so made as to yield upwardly or laterally when engaged by a misplaced bobbin.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical section through a multi-color weft replenishing mechanism looking toward the center of the loom and having my invention applied thereto.

Fig. 2 is an enlarged vertical section through the improved giveaway.

Fig. 3 is a rear end elevation of the support and its holder looking in the direction of arrow 3, Fig. 1, and

Fig. 4 is a detail elevation of the yielding nose.

Referring more particularly to the drawings it will be seen that I have provided a weft replenishing frame 10 having a plurality of guideways 11 in which bobbins normally await transfer. The bobbins are deliv-

ered one at a time by devices not shown to move to transfer position under the transferrer arm 12. A guideway 13 is pivotally mounted at the bottom of a link 14 shown in dotted lines in Fig. 1 and loosely mounted on a fixed tie rod 15. The guideway 13 has a rearwardly and upwardly extending arm 16 which has pivotal connection as at 17 with a link 18 pivoted at 19 to some fixed part of the replenishing mechanism. A spring 20 serves to hold the guideway 13 in the position shown in Fig. 1. The matter thus far described is of common construction and for further description reference may be had to Patent No. 1,030,748 and Patent No. 1,366,950.

My improvements relate more particularly to the outer support for the rear side of the bobbin and in carrying out my improvements I provide a bracket 30 adjustably held to the tie rod by set screw 31. Said bracket has a split hub 32 across which extend screws 33 serving to tighten the same. The support proper, as shown in the drawings, comprises two solid members yieldingly held together by a flexible intermediate member. The rear holding member 34 extends through the split hub and is adjustable longitudinally therein and as shown in Fig. 2 has a reduced threaded forward end 35.

Spaced from the holding member 34 is a bobbin supporting nose 36 having a rearwardly extending reduced threaded end 37 similar to the reduced end 35. A tightly wound coil spring 38 is screwed unto the ends 35 and 37, the pitch of the threads of said ends being the same as that of the coils of the spring so that the latter fits tightly on said threaded ends. Said spring 38 is stiff enough to hold the nose 36 normally in the position shown in Fig. 1 but at the time of bobbin transfer said nose will be moved downwardly to the position shown in dotted lines 50 in Fig. 2. Should the bobbin be improperly transferred so as to project above the shuttle as the same moves backwardly with the latter the nose will be moved upwardly to the position shown at 60 in Fig. 2. In making the support I find it convenient to turn the nose 36 integral with the holding member 34 and cut the threads on the same at one operation after which the two parts may be separated. This

operation insures that the axes of the two parts of the support will be coincident and that the threads will be the same.

From the foregoing it will be seen that I have provided a very simple bobbin support the yielding portion of which is movable in all angular directions with respect to the supporting structure and that the support is symmetrical about the longitudinal axis 10 thereof so as to be operable in any angular position with respect to the bracket 30.

Having thus described my invention it will be apparent that changes and modifications may be made therein by those skilled 15 in the art without departing from the spirit and scope of the invention and I do not wish to be limited to the details herein disclosed, but what I claim is:

1. In a weft replenishing mechanism, a 20 bobbin support mounted on the mechanism comprising a pair of spaced members each of which has threaded portions and a coil spring located between said members and having the ends thereof received by the 25 threaded portions, one of said members being supported entirely by said spring.

2. In a weft replenishing mechanism, a 30 bobbin support comprising a pair of spaced members one of which is held rigidly with respect to the mechanism, threaded portions formed on each member, and a coil spring having the ends thereof received by the 35 threaded portions and providing a yielding support for the other of said members, said other member being supported entirely by the spring.

3. In a bobbin support for loom weft re-

plenishing mechanism comprising a pair of spaced members each provided with a threaded portion and a coil spring having 40 the ends thereof received by the threads of the threaded portions, one of said members being supported entirely by said spring.

4. A bobbin support for loom weft replenishing mechanism comprising a pair of spaced members each having a reduced portion provided with threads, and a spring the successive coils of which are spaced the same as the threads of the reduced portions, the ends of said spring being received by 50 the portions and being threaded thereon to prevent longitudinal relative movement of the members and the spring.

5. In a loom weft replenishing mechanism, supporting structure forming part of 55 the replenishing mechanism, a bobbin support formed of two spaced members one of which is held by the supporting structure, and a resilient device having holding contact with both members to hold them in 60 spaced relation and serving as the only support for the other of said members.

6. A bobbin support for loom weft replenishing mechanism, said support comprising a pair of spaced members and a resilient device connecting the members together so that said members are relatively 65 yieldable, one of said members being supported entirely by the resilient device when the other member is secured to supporting 70 structure.

In testimony whereof I have hereunto affixed my signature.

AUGUSTIN J. CHEVRETTE.
